UNITED STATES PATENT OFFICE.

JOHN W. NEWBERRY, OF BROOKLYN, NEW YORK.

MACHINE FOR MARBLING PAPER.

No. 855,474.

Specification of Letters Patent.

Patented June 4, 1907.

Application filed February 23, 1906. Serial No. 302,424.

To all whom it may concern:

Be it known that I, JOHN W. NEWBERRY, a citizen of the United States, and a resident of Brooklyn, in the county of Kings and State of New York, have invented certain new and useful Improvements in Machines for Marbling Paper, of which the following is a specification.

This invention relates to a device which 10 may be embodied in a machine for marbling paper, the object being to simplify the construction and provide a machine which will meet all of the requirements of devices of this nature and which will produce the desired results in a simple and efficient manner.

In carrying out my invention and embodying the principal features thereof in an operative device I have provided a circular revolvable tank adapted to contain a sizing solution 20 upon which the coloring matter is distributed. This tank is adapted to be rotated in a horizontal plane by means of a central vertical shaft to which are attached radially extending arms forming supports for the aforesaid tank. Suitable standards are provided with 25 a roller forming a bearing or support and are positioned at suitable intervals under said tank. These bearings insure the even rotation of the tank which is essential to the successful operation of the machine. A carriage which is designed to hold the roll of paper to be marbleized is positioned over said tank. This carriage is provided with a mechanism for unrolling the paper and bringing successive portions of the web into contact with the 30 coloring film carried by the sizing solution as the tank is revolved. A drying device may also be provided on said carriage and the web of paper passed through the same after having taken up the colors and from thence to a 35 roll where it is finally rewound.

Various means may be used for distributing the coloring matter over the sizing solution. I have found that a device comprising 40 a rotating brush and a supply roll operated in connection with the same positioned over the tank containing the sizing solution will distribute the coloring matter upon the surface of the sizing solution and will produce the desired results in a very simple and effective manner. The construction of this portion of the device will be more fully described hereinafter.

The revolvable tank above referred is partially filled with a solution of gelatinous ma-

terial which forms the sizing or gum solution and is of such a consistency as to form a cushion on which the various colors which it is desired to transfer to the surface of the paper may be distributed. This sizing is composed of a solution of slippery elm, flaxseed and gum tragacanth, which has been found to give the best results for this purpose. The coloring material consists of earth colors, such as are usually employed for this purpose, 65 and are so arranged as to be distributed over the surface of the sizing solution in advance of the point where the paper is brought into contact with the same by means of the rotating brush and roll heretofore mentioned. 70

In the accompanying drawings I have shown my invention as embodied in a machine for the purpose set forth and in the description of this machine the more important features of my invention will be described in 75 connection with the several parts of the mechanism therein shown.

In the drawings like parts have been given similar reference numbers in the several views.

Figure 1 is a side elevation of a machine such as described showing the revolvable tank partly in section. Fig. 2, is an end elevation of the carriage showing the relative position of the same over the revolvable tank. 85 The revolvable tank and connected parts are shown in section. A vertical operating shaft is also shown in this view. Fig. 3 is a side elevation of the color distributing device.

A roll or web of paper 1 is placed in position in the carriage and the paper is fed from this roll in the direction indicated by the arrow in Fig. 1 over the guide rolls 2 and 3 to the driving roll 4, from whence it passes under the contact roll 5 into contact with the color film which has been previously distributed over the surface of the sizing solution in the circular revolvable tank in advance of this point. The paper having taken up the color under the roll 5 passes over guide rolls 6 and 7 to the rotating drum 8 from whence it is led through the drying chamber on the upper portion of the carriage and over the rotating drum 10 to the rewinding roll 11. The driving roll 4 is rotated by means of a gear 14 attached thereto which engages a circular rack 15 which revolves with the tank 17. The rotating drum 8 is driven by means of a chain or belt 9 from the shaft of the driving roll 4. The rewinding roll 11 is driven 110

by means of a belt 12 from a pulley on the shaft of the driving roll 4. A roller 13 mounted on a pivoted arm is arranged to take up the slack in the belt 12 and regulates the operation of the rewinding roll 11. The contact roll 5 is mounted upon a hand lever 16 by means of which the paper or web can be brought into contact with the color film carried by the sizing solution.

10 A supporting frame 18, which is preferably constructed with a flat circular ring to which the sizing solution tank is secured. This circular supporting ring may be provided with a plurality of radially extending arms 15 which are attached at their central or hub portion 19 to a vertical shaft 20, which is provided with suitable bearings at the upper and lower end thereof. In order to drive this shaft at the required speed a pair of 20 gears 21 and 22 may be provided, one of which is attached to the shaft 20 and the other driven by means of a pulley 23 and belt 24 from any suitable source of power.

In order to insure that the tank 17 will 25 revolve evenly over all portions of its path of travel I have provided a number of standards 25 each provided with a roller 26 at the upper end thereof. This forms a support and bearing upon which the rotating support 18 which carries the tank 17 may rest and insures the rotation of the same in an even plane.

As a portion of the sizing solution is being 30 constantly taken away with the coloring matter by the paper it is necessary to provide means for renewing the same in order to keep a constant amount in the tank. In order to provide for this requirement I have mounted a reservoir 27 upon the driving shaft 20 and have provided supply pipes, such as 28, leading to the circular tank 17. An overflow receptacle 29 in the form of an 35 annular recess separated from the tank 17 by a dividing wall which is cut away at suitable intervals to provide for the overflow of the sizing solution into this receptacle furnishes a convenient means of keeping the sizing solution in the tank 17 at a constant level. The overflow solution is drawn off from the receptacle 29 by means of one or more pipes, such as 30, to a receptacle 31 carried by the driving shaft 20 and from which it may be drawn off by means of a suitable valve 32 into a stationary receptacle 33 from which it is 40 pumped by a suitable pumping device back to the reservoir 27. The reservoir 27 and the receptacle 31 with their attached pipes revolve with the driving shaft 20 and the tank and overflow 17 and 29.

60 The driving mechanism for revolving the tank and the feeding mechanism by means of which the paper on the carriage is fed successively into contact with the color film carried by the sizing solution is so designed that 65 the tank will be revolved at the same speed

as that of the paper as it passes under the contact roll 5 and consequently there will be no relative movement between the color film and the paper at this point. In the making of some designs in order to get the required 70 effect it may be found desirable to produce a slight relative movement and this may be done by moving the carriage or the contact roll by any desired means. In the ordinary use of the machine however the carriage remains stationary and the tank revolves underneath the same, as described.

One of the important features of my invention is the distributing device for supplying the coloring material to the surface of the 80 sizing solution. This device is shown in detail in end elevation in Fig. 3. A receptacle 34 is adapted to receive the coloring material, which is supplied thereto from any suitable reservoir, such as 35, which may be carried 85 on a suitable support 36. A roller 37 mounted in a suitable bearing 38 supplies the coloring material in the receptacle 34 to the distributing brush 39. This brush is carried in an adjustable block or support 40 which is 90 controlled by a set screw 41. An idler gear 42 is rotated by the revolving rack 15 and in turn rotates the gears 43 and 44 attached to the shafts of the color roll 37 and the brush 39, respectively. This causes the brush and 95 roll to revolve in the direction indicated by the arrows. A wire stop 45 mounted upon adjustable support 46 is so positioned in relation to the brush as to engage the outer end of the bristles thereof causing the coloring 100 material which has been taken from the color roll 37 to be spattered over the surface of the sizing solution in the tank over which the device is placed. A hinged and perforated cover 47 is provided over the receptacle 34 and through the perforated cover the coloring material is strained removing any foreign substances in the same. A perforated regulator and overflow stop 48 is attached to the forward end of the receptacle 34. The space 105 between the inner edge of this stop and the color roll 37 regulates the amount of coloring material that will be carried to the brush 39 and this stop also prevents the coloring material from slopping over the edge of the receptacle 34. The perforations in this stop are for the purpose of allowing the drippings from the brush to fall back into the receptacle. A drip pan 49 is also provided to 110 catch any coloring matter which might otherwise fall onto the surface of the sizing solution and disturb the pattern of colors. Any number of these distributing devices may be used depending upon the number of different colors which it is desired to use. It will be 115 also evident that while this device is here shown in connection with a revoluble tank that it may also be used with other types of machines for this purpose. By varying the size of the driving gears the speed of the 120

130

brush or roll may be varied and on account of the adjustable block for changing the position of the brush and also the adjustable stop which intercepts the bristles, it will be seen that the effect produced in the color film may be regulated as desired.

The device herein shown and described illustrates an embodiment of my invention in a practical machine for the purpose set forth which I have found after numerous experiments to give the best results. I do not confine myself, however, to the exact details of construction or to the design and arrangement of the several parts of the machine herein shown and described, as it will be evident that various changes may be made therein without departing from the scope of my invention.

What I claim is:

1. In a marbling machine, the combination of a revoluble tank adapted to contain a sizing solution, a carriage adapted to carry the paper to be marbleized, means for revolving said tank in a horizontal plane, means for distributing coloring matter over said solution, and means for passing the paper successively into contact with the color film carried by said sizing solution.

2. In a marbling machine, in combination, a tank for containing sizing solution, said tank being mounted so as to be revolved in a horizontal plane, about a central point, means for revolving said tank, a carriage adapted to carry the paper to be marbleized, means for distributing coloring matter over said sizing solution, and means for passing the paper successively into contact with the color film carried by said sizing solution.

3. In a marbling machine, in combination, a circular tank for containing sizing solution, said tank being mounted so as to be revolved in a horizontal plane, about its center, means for revolving said tank, a carriage adapted to carry the paper to be marbleized, means for distributing coloring matter over said sizing solution, and means for passing the paper successively into contact with the color film carried by said sizing solution.

4. In a marbling machine, in combination, a tank for containing sizing solution, said tank being mounted so as to be revolved in a horizontal plane, about a central point, means for revolving said tank, a stationary carriage adapted to carry the paper to be marbleized, means for distributing coloring matter over said sizing solution, and means for passing the paper successively into contact with the color film carried by said sizing solution.

5. In a marbling machine, the combination of a revoluble tank adapted to contain a sizing solution, means for maintaining a constant amount of said sizing solution in said tank, a carriage adapted to carry the paper to be marbleized, means for revolving said

tank in a horizontal plane, means for distributing coloring matter over said solution, and means for passing the paper successively into contact with the color film carried by said solution.

6. In a marbling machine, the combination of a revoluble tank adapted to contain a sizing solution, a reservoir adapted to contain surplus solution, a pumping device adapted to transfer said solution to said reservoir, a supply pipe leading from said reservoir for maintaining a constant amount of said sizing solution in said tank, means for revolving said tank, in a horizontal plane, a carriage for carrying the paper to be marbleized, means for distributing coloring matter over said solution, and means for passing the paper successively into contact with the color film carried by said sizing solution.

7. In a marbling machine, the combination of a revoluble tank adapted to contain a sizing solution, a reservoir adapted to contain surplus solution, a pumping device adapted to transfer solution to said reservoir, a plurality of supply pipes leading from said reservoir for maintaining a constant amount of said sizing solution in said tank, means for revolving said tank, in a horizontal plane, a carriage adapted to carry the paper to be marbleized, means for distributing coloring matter over said solution, and means for passing the paper successively into contact with the color film carried by said sizing solution.

8. In a marbling machine, the combination of a revoluble tank adapted to contain a sizing solution, a rack adapted to revolve with said tank, means for revolving said tank and rack, in a horizontal plane, a rotatable brush adapted to distribute coloring matter over said sizing solution having a gear attached thereto adapted to operatively engage said rack, a carriage adapted to carry the paper to be marbleized, and means for passing the paper successively into contact with the color film carried by said sizing solution.

9. In a marbling machine, the combination of a revoluble tank adapted to contain a sizing solution, a rack adapted to revolve with said tank, means for revolving said tank and rack, in a horizontal plane, a rotatable brush and roll driven by means of said rack and adapted to distribute coloring matter over said sizing solution, a carriage adapted to carry the paper to be marbleized, and means for passing the paper successively into contact with the color film carried by said sizing solution.

10. In a marbling machine, the combination of a circular revoluble tank adapted to contain a sizing solution, a carriage adapted to carry the paper to be marbleized, means for revolving said tank, in a horizontal plane, means for distributing coloring matter over

said solution, and means for passing the paper successively into contact with the color film carried by said sizing solution.

11. In a marbling machine, the combination of a circular revoluble tank adapted to contain a sizing solution, a circular rack adapted to revolve with said tank, means for revolving said tank and rack, in a horizontal plane, a rotatable brush operated by said rack and adapted to distribute coloring matter over said sizing solution, a carriage adapted to carry the paper to be marbleized, and means for passing the paper successively into contact with the color film carried by said sizing solution.

12. In a marbling machine, the combination of a revoluble tank adapted to contain a sizing solution, a receptacle adapted to receive the overflow solution from said tank, means for revolving said tank, in a horizontal plane, means for distributing coloring matter over the solution in said tank, and means for passing the paper successively into contact with the color film carried by said sizing solution.

13. In a marbling machine, the combination of a circular revolving tank adapted to contain a sizing solution, a circular receptacle adapted to receive the overflow solution from said tank, means for revolving said tank, in a horizontal plane, means for distributing coloring matter over the solution in said tank, and means for passing the paper successively into contact with the color film carried by said sizing solution.

14. In a marbling machine, the combination of a circular revoluble tank adapted to contain a sizing solution, a circular receptacle adapted to be revolved with said tank and to receive the overflow solution therefrom, means for revolving said tank and receptacle, means for distributing coloring matter over the solution in said tank, and means for passing the paper successively into contact with the color film carried by said sizing solution.

15. In a marbling machine, the combination of a revoluble tank adapted to contain a sizing solution, a carriage adapted to carry the paper to be marbleized, a driving shaft operatively connected with said tank and adapted to revolve the same, in a horizontal plane, means for distributing coloring matter over said solution, and means for passing the paper successively into contact with the color film carried by said sizing solution.

16. In a marbling machine, the combination of a revoluble tank adapted to contain a sizing solution, a vertical driving shaft centrally located and operatively connected with said tank to revolve the same, in a horizontal plane, a carriage adapted to carry the paper to be marbleized, means for distributing coloring matter over said solution, and means for passing the paper successively

into contact with the color film carried by said sizing solution.

17. In a marbling machine, the combination of a circular revoluble tank adapted to contain a sizing solution, means for revolving said tank, in a horizontal plane, means for distributing coloring matter over said solution, a support positioned under said tank, a carriage adapted to carry the paper to be marbleized, and means for passing the paper successively into contact with the color film carried by said sizing solution.

18. In a marbling machine, the combination of a circular revoluble tank adapted to contain a sizing solution, means for revolving said tank, in a horizontal plane, means for distributing coloring matter over said solution, a support carrying a roller forming a bearing under said tank, a carriage adapted to carry the paper to be marbleized, and means for passing the paper successively into contact with the color film carried by said sizing solution.

19. In a marbling machine, the combination of a circular revoluble tank adapted to contain a sizing solution, means for revolving said tank, in a horizontal plane, means for distributing coloring matter over said solution, a plurality of supports positioned under said tank, a carriage adapted to carry the paper to be marbleized, and means for passing the paper successively into contact with the color film carried by said sizing solution.

20. In a marbling machine, the combination of a circular revoluble tank adapted to contain a sizing solution, means for revolving said tank, in a horizontal plane, means for distributing coloring matter over said solution, a plurality of supports positioned under said tank each provided with a roller forming a bearing for retaining said tank in a level position, carriage adapted to carry the paper to be marbleized, and means for passing the paper successively into contact with the color film carried by said sizing solution.

21. In a marbling machine, the combination of a revoluble tank adapted to contain a sizing solution, a centrally located shaft operatively connected to said tank for revolving the same, in a horizontal plane, a reservoir surrounding said shaft and adapted to supply sizing solution to said tank, means for distributing coloring matter over said solution in said tank, a carriage adapted to carry the paper to be marbleized, and means for passing the paper successively into contact with the color film carried by said sizing solution.

22. In a marbling machine, the combination of a revoluble tank adapted to contain a sizing solution, a support for said tank, means for revolving said support and tank, in a horizontal plane, means for distributing coloring matter over said solution in said tank, a carriage adapted to carry the paper to be marbleized, and means for passing the

paper successively into contact with the color film carried by said sizing solution.

23. In a marbling machine, the combination of a revoluble tank adapted to contain a sizing solution, a vertical shaft for revolving said tank, in a horizontal plane, a reservoir carried by said shaft, pipes leading from said reservoir to said tank, an overflow receptacle positioned so as to receive overflow solution from said tank, pipes leading from said overflow receptacle to a receptacle carried by said shaft, means for transferring the solution from said last named receptacle to said reservoir, means for distributing coloring matter over said sizing solution, a carriage for carrying the paper to be marbled, and means for passing the paper successively into contact with the coloring film carried by said sizing solution.

24. A color distributing device adapted

for use with a machine for marbling paper, said device having a receptacle for receiving the coloring material, a rotating brush adapted to distribute said coloring material over a sizing solution, a roller adapted to carry the coloring material from said receptacle to said brush, a perforated cover through which said coloring material is strained before entering said receptacle, a regulator for controlling the amount of coloring matter carried to said brush, and means for rotating said brush and roller.

Signed at New York in the county of New York and State of New York this 21st day of Feb. A. D. 1906.

JOHN W. NEWBERY.
